UNITED STATES PATENT OFFICE.

JOHN F. BROWN, OF PHENIX, RHODE ISLAND.

RUNNING-BOARD FOOTPLATE.

Application filed August 23, 1922. Serial No. 583,812.

To all whom it may concern:

Be it known that I, JOHN F. BROWN, a citizen of the United States, residing at Phenix, in the county of Kent and State of Rhode Island, have invented certain new and useful Improvements in Running-Board Footplates, of which the following is a specification.

This invention relates to improvements in auxiliary foot plates such as are employed upon the running boards of automobiles and has as its primary object to so construct the foot plate that it will serve as an identifying means enabling one to readily locate his machine among others thus avoiding confusion and effecting a saving in time.

In the accompanying drawings—

Figure 1 is a perspective view of the foot plate embodying the invention installed upon the running board of an automobile;

Figure 2 is a sectional view taken substantially on the line 2—2 of Figure 1 looking in the direction indicated by the arrows.

The foot plate embodying the invention is indicated in general by the numeral 1 and the same is preferably cast from aluminum and comprises a substantially flat rectangular body 2 which may be roughened upon its upper surface as usual as indicated by the numeral 3 and secured in place upon the running board of the machine, indicated by the numeral 4, by screws, bolts, or other fastening elements 5. Such plates are ordinarily provided with an upstanding flange at their edges next adjacent the running board shield of the car, which shield is indicated by the numeral 6. Heretofore, however, these flanges have served no other purpose than as a guard to prevent denting or scratching of the running board shield when one steps upon the foot plate, but the present invention contemplates adapting this flange to perform an additional function as will now be explained.

In the drawings the flange referred to above is indicated by the numeral 7 and in carrying out the principles of the invention, the flange is formed with open letters, symbols, or the like, indicated by the numeral 8 which may comprise the name of the

owner of the automobile, the name of the maker, the town or city in which the owner resides, etc., and will in any event constitute an identifying means which will enable the owner of the machine to more readily locate the same among others. The flange 7 upstands beside the running board shield 6 and as the letters or symbols 8 are open, the color of the finish of the machine or, more specifically, the running board shield, will be visible through the open letters or characters. Therefore, if the foot plate is formed of aluminum or some other so-called white metal, and if the body of the machine is of a distinctive color, the letters or characters 8 will stand out boldly and be readily discernible.

In carrying out the invention and in molding the foot plates, they may be cast in molds provided with interchangeable and selectively arrangeable letter or character cores permitting of different names or combinations of letters or characters being set up and thus reproduced in the flange of the plate as it comes from the mold. Therefore the invention presents not only the advantage that the article as finished will constitute an identifying means, but also it possesses commercial advantages in that a manufacturer placing his machines upon the market may equip each machine with a set of foot plates bearing the purchaser's name or any other selected mark of identification which might be preferred by him.

Having thus described the invention, what is claimed as new is:

1. A foot plate for automobiles comprising a body provided with a flange to upstand beside the running board shield of the automobile upon the running board of which the foot plate is to be installed, the said flange having an identification character or the like formed therein and defined by an opening extending entirely through said flange whereby the distinctive color of the finish of the running board shield will be visible through said opening in contrast with the color of the metal of which the foot plate is formed.

2. The combination with the running

board and running board shield of an automobile, of a foot plate secured upon the running board and having a flange upstanding beside the shield, the flange having open characters or the like formed therein and constituting an identification means, the finish of the said shield being visible through

the openings defining the characters in contrast with the color of the metal of which the foot plate is formed and thereby being 10 readily discernible.

In testimony whereof I affix my signature.

JOHN F. BROWN. [L.S.]
